UNITED STATES PATENT OFFICE.

ANDREW L. RIKER, OF BRIDGEPORT, CONNECTICUT, ASSIGNOR TO THE "LOCOMOBILE" COMPANY OF AMERICA, OF NEW YORK, N. Y., A CORPORATION OF WEST VIRGINIA.

INTERNAL-COMBUSTION ENGINE.

1,194,068.

Specification of Letters Patent.

Patented Aug. 8, 1916.

Application filed February 21, 1911. Serial No. 609,872.

To all whom it may concern:

Be it known that I, ANDREW L. RIKER, a citizen of the United States, and a resident of Bridgeport, county of Fairfield, State of Connecticut, (whose post-office address is Bridgeport, Connecticut,) have invented an Improvement in Internal-Combustion Engines, of which the following description, in connection with the accompanying drawings, is a specification, like letters on the drawings representing like parts.

This invention relates to internal combustion engines, and particularly to the means for controlling the admission of fuel to the cylinder and the exhaust of the waste gases therefrom.

The invention will be best understood by reference to the following description when taken in connection with the accompanying illustration of one specific embodiment thereof, while its scope will be more particularly pointed out in the appended claims.

In the drawings: Figure 1 is a central 25 sectional elevation taken through a cylinder of an internal combustion engine embodying one form of the invention; Fig. 2 is a detail showing the cam and actuating link for actuating the controlling valve; Fig. 3 is a section similar to Fig. 1 showing a modified form of the invention; Fig. 4 is an elevation partly in section showing the construction of the split rings employed in connection with the valve; and Fig. 5 is a plan 35 view of the rings shown in Fig. 4.

Referring to the drawings and particularly to the illustrated embodiment of the invention shown in Fig. 1, there is provided a main cylinder 1 having a water jacket 2 secured to the crank casing 3. The engine may consist of a single cylinder or a plurality of cylinders, the application of the invention to a multiple cylinder engine being evident from the description herein contained of its embodiment in a single cylinder engine. The cylinder is provided with inlet and outlet ports 4 and 5, respectively, which are preferably in the form of circumferential openings extending completely 45 around the cylinder except where it may be necessary to interrupt them by one or more strengthening ribs 6 and 7. These ports communicate with passages extending completely around the cylinder and are connected respectively by the inlet passage to

the supply pipe at 8 on one side of the cylinder, and by the outlet passage to the exhaust pipe at 9 on the opposite side of the cylinder. The engine is provided with a working piston 10 connected by the rod 11 to the crank 12 and the crank shaft 13, all of usual construction. It is also provided with a cylinder head 14 containing the spark plug 15 and provided with the water jacket chamber 16 which is in communication with the cylinder water jacket 2.

While the invention is applicable to other types of engines, herein an engine of the Otto-cycle type is shown, wherein the admission to and exhaust from the working space of the cylinder is controlled by a sleeve valve 17. While the sleeve may occupy other relations, herein it is interposed between the piston member 10 and the cylinder member 1 and moved longitudinally in sliding contact with the walls of each member, acting to control communication between the working space of the cylinder and the inlet and outlet ports 4 and 5. To actuate the sleeve the latter is connected at its lower end (Fig. 2) by the link 18 to the bell crank lever 19 pivoted at 20 on the crank case, the opposite arm of the lever carrying a cam roll 21 which engages with the track cam 22 and is thereby given movement to appropriately actuate the sleeve 17. The cam is herein mounted upon a countershaft which is driven from the crank shaft through the gears 24 and 25 (represented in dotted lines, Fig. 1), at one-half the speed of the crank shaft, as is usual in valves of this type, so that the sleeve executes one full reciprocation for each two reciprocations of the working piston. In engines employing valves of this type it has been difficult to construct the ports so as to prevent leakage and particularly in and about the cylinder head under the high pressure obtaining during the working stroke. It has been attempted to secure good results by giving the upper prolonged end of the sleeve valve a sliding fit between the walls of the cylinder and the reentrant walls of the cylinder head. This, however, is neither a satisfactory construction nor does it adequately prevent the leakage referred to. Herein I secure a substantially tight fit between the valve and the cylinder, and greatly simplify the construction of the co-operating parts, by making the working

portion of the valve where it controls the ports in the form of one or more split expansion rings adapted to control the cylinder ports and at the same time to press outwardly against the cylinder walls under the working pressure within, the overlap of such rings being sufficient to prevent any substantial leakage. Such a form of valve provides an ideal construction for this type 10 of engine, since its resistance to leakage increases directly with the working pressure in the cylinder and therefore with the increased necessity for such resistance.

Referring to the drawings, it will be seen 15 that the upper portion of the sleeve 17 where it overlies the ports 4 and 5 is provided with a recess in which is seated a pair of concentric split expansion rings 26 and 27. The two rings are provided with a series of 20 ports 28 and 29, respectively, extending circumferentially around the rings, the ports of one ring being in registration with those of the other and being also in registration with a series of ports 30 formed in the walls 25 of the sleeve 17, so that, as the latter is raised or lowered, these ports act to open the working space of the cylinder alternately to the exhaust or to the admission passages. The rings and sleeve are kept in 30 fixed circumferential relation by any suitable means such as the pin 31 (Fig. 1). To press the rings outwardly, the sleeve is provided with openings of suitable number and size to expose the inner walls of the rings 35 to the pressure within the cylinder space. Herein two rows of such openings 32 and 33 are shown, these openings or a number of them also passing through the inner ring 27 so that the outer ring 26 is directly exposed 40 to cylinder pressure. It therefore follows that when the engine is compressing a charge or firing the same both rings are expanded and pressed outwardly under a force proportional to internal pressure, and the 45 resistance of the valve to leakage is correspondingly increased. The pressure applied to the rings may be increased or reduced by increasing or reducing the area of the ring portions exposed to the internal pressure. 50 In some cases no perforations in the inner ring 27 may be necessary, the pressure on the inner ring being sufficient to seat the outer ring against the ports with the required pressure. Since the rings are definitely located circumferentially of the sleeve, 55 the split portion of the outer ring may be arranged to lie opposite the ribs 6 and 7. Preferably the split portions of the two rings are located out of register with each 60 other and preferably those of each ring are located at diametrically opposite points (see Fig. 5 wherein the divisions of the outer ring are indicated by the reference letter *a* and those of the inner ring by the reference letter *b*). This location of the split por-

tions is desirable for the reason that leakage is thereby greatly decreased.

The cam 22 is so formed as to give the proper timing of the valve with reference to admission, compression, firing and exhaust. 70 On the charging stroke of the piston the valve is lowered to open the inlet port 4 through the sleeve ports to the working space of the cylinder, the valve moving back to close the ports on the return or compression stroke. During the firing stroke the valve moves still farther back so that when the exhaust stroke commences it has opened the exhaust port 5 to the cylinder space. When the exhaust stroke is completed the 80 valve moves quickly forward (as represented in Fig. 1) to open the admission port 4.

It will be seen that the reentrant walls of the cylinder head 14 do not necessarily have contact with the walls of the sleeve. While 85 they may have such contact, preferably a slight clearance is provided as shown, the space between the cylinder and the sleeve being preferably so proportioned that on the exhaust stroke the sleeve substantially fills 90 such space and expels all gases therefrom.

In Fig. 1 the sleeve is shown as having a uniform external diameter, the internal diameter of the sleeve being reduced to provide the recess for the expansion rings. This 95 construction will ordinarily leave a clearance sufficiently small to give the required compression, but if a smaller clearance space is desired, or, for other reason, it may be required to have the piston travel back farther through the sleeve, the latter may be of a uniform internal diameter as represented in Fig. 3, the expansion rings therein being contained in a recess formed between raised portions 34 and 35 on the sleeve. This 105 provides means for further limiting the clearance space if desired, the construction otherwise being the same as that shown in Fig. 1.

While I have herein shown and described for purposes of illustration one specific form of the invention, it is to be understood that the latter is not limited to the precise construction disclosed nor to the form or relative arrangement of parts nor to the particular type of engine described, but that extensive modifications may be made in the illustrated embodiment of the invention without departing from the spirit thereof.

Claims:

1. In an internal combustion engine the combination with a cylinder having inlet and outlet ports, a working piston, a movable sleeve between the piston and cylinder, means for imparting an intermittent motion 115 to said sleeve and a split expansion ring carried by said sleeve and adapted to overlie said cylinder ports, said ring being exposed to the working pressure of the cylinder and having ports to register with ports 120

- in the sleeve whereby communication between the inlet and outlet ports and the working space of the cylinder is controlled.
2. In an internal combustion engine, the combination with a cylinder having inlet and outlet ports, a working piston, a sleeve movably arranged between the piston and cylinder, means for actuating said sleeve, a split expansion ring carried by said sleeve and overlying said ports, a second split expansion ring between said outer ring and the sleeve, said rings and sleeve having ports in registration and adapted to control communication between the working space of the cylinder and the said inlet and outlet ports and said sleeve also being perforated to expose said rings to the pressure of the cylinder space.
3. An internal combustion engine having a cylinder, one or more ports therein, a working piston, a sleeve having one or more ports to control the cylinder port or ports, a split expansion ring having a port or ports in registration with the ports of the sleeve, said ring being carried by said sleeve and being adapted to overlie said cylinder port or ports, and means to impart an intermittent motion to said sleeve.
4. In an internal combustion engine the combination with a cylinder provided with a port or ports, a working piston, a sleeve having a port or ports to control communication between the cylinder space and the cylinder ports, a split expansion ring carried by said sleeve and adapted to coöperate with said cylinder port or ports, and means to impart an intermittent motion to said sleeve.
5. In an internal combustion engine the combination with a working piston of a ported cylinder, a sleeve valve controlling said ports, the working portion of said valve including a split expansion ring adapted to travel over the cylinder ports, and means to impart an intermittent motion to said sleeve.
6. In an internal combustion engine the combination with a working piston of a ported cylinder, a sleeve valve controlling said ports, the working portion of said valve including a split expansion ring adapted to travel over the cylinder ports, said ring being exposed to the pressure of the cylinder space, and means to impart an intermittent motion to said sleeve.
7. In an internal combustion engine the combination with a ported cylinder of a working piston, a ported expansion ring with means for causing the same to travel over the cylinder ports and control communication between the same and the cylinder space, and means to impart an intermittent motion to said ring.
8. In an internal combustion engine the combination with a ported cylinder of a piston, a sleeve valve controlling communication between the cylinder port and cylinder space, said valve including a split expansion ring exposed to the pressure of the cylinder space, and means to impart an intermittent motion to said valve.
9. In an internal combustion engine the combination with a ported cylinder of a working piston and sleeve valve having a plurality of concentric split expansion rings exposed to the pressure of the cylinder space and controlling communication between the latter and the cylinder port or ports, the splits of said rings being out of register with each other.
10. An internal combustion engine having a cylinder provided with an annular port interrupted by a rib forming a continuation of the internal cylindrical wall of the cylinder, an expansion ring having a split in alinement with said rib, and means for causing said ring to travel over said port and control communication between the same and the cylinder space, while maintaining the alinement of said split with said rib.
11. An internal combustion engine having a cylinder provided with an annular port interrupted by a rib forming a continuation of the internal cylindrical wall of the cylinder, a plurality of concentric split expansion rings, the outer expansion ring having a split in alinement with said rib, and the other ring or rings having a split or splits out of alinement therewith, and means for causing said rings to travel over said port and control communication between the same and the cylinder space while still maintaining the alinement of the split portion of the outer rings with said rib.
12. An internal combustion engine having a piston, a crank shaft, a cylinder provided with admission and exhaust ports, a sleeve mounted to slide upon the walls of the cylinder between the same and the piston, means for reciprocating said sleeve once for each two revolutions of the crank shaft, said sleeve having a ported split portion covering the said ports and adapted to control admission and exhaust through said ports.
13. In an internal combustion engine the combination with a fixed cylinder having a bore of uniform diameter, oppositely disposed admission and exhaust ports at the rear of the working space, a piston, a pair of arc-shaped valve members beyond the rearward limit of piston travel, and means for moving said members for opening and closing said ports.
14. In an internal combustion engine the combination with a cylinder having admission and exhaust ports in the explosion chamber, a piston, slide valve plates arranged to open and close said ports and located beyond the rearward limit of piston travel.

travel, said valve plates being exposed to the pressure of the working cylinder space, and means for moving said plates for opening and closing said ports.

15. An internal combustion engine comprising a cylinder having a water-jacketed working space, a water-jacketed cylinder head, said cylinder having admission and exhaust ports, arc-shaped valve members automatically seated by exposure to the pressure of the gas within the cylinder, said

plates working between the walls of the cylinder and the cylinder head and out of the direct path of heat dispersion from the working space to the water-jacket.

In testimony whereof, I have signed my name to this specification, in the presence of two subscribing witnesses.
